UNITED STATES PATENT OFFICE.

HENRY B. WILLIAMS, OF ROCHESTER, NEW YORK, ASSIGNOR OF ONE-HALF
TO LEMUEL A. JEFFREYS, OF SAME PLACE.

PACKAGE-CARRIER.

SPECIFICATION forming part of Letters Patent No. 433,111, dated July 29, 1890.

Application filed December 28, 1889. Serial No. 335,251. (No model.)

To all whom it may concern:

Be it known that I, HENRY B. WILLIAMS, of Rochester, in the county of Monroe and State of New York, have invented a certain 5 new and useful Improvement in Package-Carriers; and I do hereby declare that the following is a full, clear, and exact description of the same, reference being had to the drawings accompanying this application.

10 My improvement relates to package-carriers for stores, &c., designed to convey goods in a basket or similar receptacle on a track leading from the counter or place where the goods are purchased to a cashier's desk, where the 15 goods are then wrapped and returned over another track to the place of starting, together with the difference in money between the deposit and the amount of purchase. Such devices are well known and in common use in 20 large retail stores.

My invention consists in the construction and arrangement of parts hereinafter fully described, and embodied in the claims.

In the drawings, Figure 1 is a diagram showing a plan view of the double track, including the cashier's station at the left and one of the salesmen's stations at the right, the main track extending beyond the last-named station and being broken off. Fig. 2 is a side 25 elevation of Fig. 1. Fig. 3 is a side elevation of a portion of the track on the side leading from the salesmen's to the cashier's stations, and showing more particularly the switch on that side for elevating the carrier and running it onto the main track. Fig. 4 is an enlarged plan view of the end of the track at the cashier's station. Fig. 5 is a similar view at one of the salesmen's stations, and showing a plan view of the carrier in passing 30 around the curve at the place of deposit after returning from the cashier. Fig. 6 is a cross-section in line $x-x$ of Fig. 5. Fig. 7 is an elevation looking on the inner side of the track leading from the cashier to the salesman and 35 showing the switch on that side, and the car in position for operating the switch to carry the car from the main track to the place of deposit below. Fig. 8 is a cross-section of the track and a rear elevation of the carrier. Fig. 9 is an enlarged face elevation of the 40 upper part of the carrier, showing the means

for adjusting the tripping-arm higher or lower. Fig. 10 is a cross-section of Fig. 9 in line $y-y$. Fig. 11 is an enlarged cross-section in line $z-z$ of Fig. 2. Fig. 12 is an enlarged 55 cross-section of the traveling cord or cable and an elevation of the open fork on the top of the carrier which engages with the cord.

A and A' are the two main tracks, the first leading from the salesman to the cashier, and 60 the latter being the return-track.

B is the cashier's station and C the salesman's station, of which one or more may be used.

D is the carrier or car which runs on the 65 track, being in the form of a basket or other suitable receptacle.

The return-track A' has, at a point a little back from the receiving-station C, an arm E, which is pivoted at a, so as to turn up and 70 down, the opposite end playing free and registering with the main track when raised and with the curved receiving-track C when lowered, as indicated by the full and dotted lines in Figs. 2 and 7. This arm forms a switch 75 to carry the carrier from the main return-track to the receiving-station after it has left the cashier.

F, Fig. 7, is a sliding bolt resting loosely in ways $b-b$ on the inner side of the switch E, 80 the outer end c shooting past the joint between the end of the switch and the main rail and resting in a socket d, which supports it and thus holds the switch in alignment with the main track. At the opposite end of 85 the bolt is pivoted a connecting-rod f, pivoted at its opposite end to a rock-pin g, pivoted to a bearing h. When the rock-pin is thrown forward, it draws on the connecting-rod f and thereby retracts the bolt F and unlocks the 90 switch E, allowing it to fall. A spring i, attached at one end to the bolt and at the other to the switch, draws the bolt forward again in position to be locked when raised. The locking end of the bolt is inclined to enable 95 it to spring past the socket with which it engages in rising. The switch is raised by a spring j, attached to the hanger G or some other stationary part.

H, Figs. 9 and 10, is a slide moving up and 100 down vertically in the head of the carrier D, said slide being held at any adjustment by

means of a pointed dog k , attached to a shank k' , pivoted at k^2 , and provided with a finger-knob k^3 , pressed up to place by a spring k^4 . To change the adjustment of the slide the 5 dog is withdrawn from one of a series of notches $l l l$ in the plate in which it rests and entered into another higher or lower. m is a fixed stud attached to the adjustable slide and projected inward to such a degree as to 10 strike and trip the rock-pin g and thereby release the switch, as before described. The object of the adjustment of the slide is to raise the stud m , so that while it trips and operates its own pin, it will pass over and escape the other pins at other stations. 15

It is designed to use several receiving-stations, which are necessary in most stores, and in order to allow the carriers for the remote stations to pass over the track without operating the switches of the nearer stations the rock-pins $g g$ of the several stations are made of different heights, those at the remoter stations being the highest, and the studs $m m$ are correspondingly adjusted higher to pass 20 over the first pins and strike only the one at its own station. Thus arranged, when the carrier arrives at its station it strikes the rock-pin g at that station, the switch E falls, and the carrier passes from the main 25 track down over the switch and onto the curved receiving-track C , which stands at a lower level and within reach of the attendant. The switch is depressed by the load of the carrier, and when the carrier has passed 30 from it the switch is drawn back by the spring j , as before described. The carrier is provided with flanged wheels $n n$, which run on the track—one in advance of the other—and these flanged wheels are attached to spindles 35 $o o$, which turn axially in bearings $p p$ of the carrier. By this means the wheels can turn sufficiently to adapt themselves to the curvature of the track, and cramping and binding are prevented. $q q$, Figs. 7 and 8, are springs 40 which ride under the track and prevent the wheels from being thrown off. The lower portions of these springs are inclined so that they can yield in passing the switches by striking an incline r at the contiguous end 45 of the curved track C .

I is an arm, pivoted at s to the other track A , that leads from the receiving-station to the cashier's station. The free end of this arm, when lowered, connects with and forms 50 a continuation of the curved track C , and inclines up to the main track above. The carrier, in passing around the curve C , is carried onto the end of arm I by its momentum, and is retained there when it stops by means 55 of a projection t , Figs. 3 and 5, forming a catch with which engages one of the springs q on the carrier, said spring yielding in passing over it and then springing out behind it. u is a link, pivoted at one end to the free end 60 of arm I , and having at the other a socket-piece v , Fig. 3, which slides on a hanger or other support G .

e is a cord or chain, attached at one end to the link u , thence extending up over a pulley a^2 on the hanger and thence down within 70 reach of the operator. By drawing on the cord the arm I will be raised, as indicated by the dotted lines, Fig. 3, and with it the carrier, and in this condition it stands at an incline, and the carrier will run down automatically onto the main track in the direction of the cashier's station. 75

K , Fig. 3, is a switch in the track A , pivoted at b^2 and provided with a beveled free end b^3 , that shuts down on top of the main 80 track and forms a connection at that point.

c^2 , Fig. 11, is a vertical arm attached to switch K , and d^2 is a similar vertical arm attached to the elevator-arm I , the two lying in line. The arm d^2 is slotted, as shown at f^2 . 85

g^2 is a bearing attached rigidly to arm a^2 and passing loosely through the slot f^2 , the arm d^2 sliding freely up and down on the bearing. When the elevator-arm I is raised, as before described, to run the carrier onto the 90 main track, the switch K will be raised, as shown by dotted lines, Fig. 3, to clear the way for the carrier, the latter running under it. When the arm I is lowered again, the switch K falls and makes the connection for other 95 carriers on the main track. At the same time the slot f^2 is of such length that it allows the arm I to be lowered below the curved track C , as indicated by the dotted lines at the bottom in Fig. 2, so that in those places where the 100 curved track C is so high that the carrier cannot be readily reached it can be lowered to the desired degree to insert or remove the goods.

In this invention it is designed that the carrier shall never be removed from the track in handling the goods, but always remain in place and in condition for running forward or back. In its normal position the free end of the arms I rests in alignment with the end 105 of the curved track C and is held by a spring-hook h^2 , Fig. 3; but to lower it to the position shown by the dotted lines, Fig. 2, the hook is sprung back by hand to free the end of the arm. When the arm is raised again, it automatically engages with the spring-hook. 115

L , Figs. 5 and 6, is a spring-arm pivoted at i^2 to a cross-bar or other stationary device in the curved track C and adapted to swing forward and back in a half-circle. It is thrown 120 back to the left by a torsion-spring l^2 . It is provided at its outer end with an upright hook m^2 , and with this hook engages a horizontal hook n^2 on the head of the carrier D . When the carrier runs down the incline and 125 passes onto the curved track C , the hook n^2 strikes hook m^2 and carries the arm L around with it and winds up the torsion-spring l^2 . At the extreme of the turn C the spring-arm L passes under a cam u^2 , which depresses it and 130 frees it from hook n^2 , leaving the carrier to run forward, while the arm itself springs back to its former position. This spring-arm serves a double purpose. First, it catches the carrier 135

and prevents the rocking or swaying motion of the latter in passing around the circle, and, secondly, it gradually retards the motion of the carrier, so that when it reaches the elevating-arm I it is nearly still.

M is an endless cord or cable located above the tracks A A' and running in the directions in which the carrier is to travel, both in going to and from the cashier's station. It has at intervals enlargements $p^2 p^2$ thereon, conveniently made by clamping small thimbles around the cord, as shown in Fig. 12. On the front standard o of the carrier is a forked open-topped extension o', Fig. 12, which embraces the cord and is driven forward by one of the shoulders p^3 striking it in the rear. By this means the carrier is propelled as fast as the cord moves. At those points where the carriage is deflected from the main course, as in passing down the switch E, the fork separates from the cord, and in passing from the arm I onto the main track it strikes under and engages with it again.

At the cashier's station B the tracks A A' are bent down, so that the track stands at a lower level, and at this point the cord M is at such a height that the carrier frees from the cord and runs back on the track, where it is stopped. At this point the cord passes around pulleys $r^2 r^2$, which stand in advance of the rear end of the track, leaving the carrier unimpeded and free, as shown in the plan view, Fig. 4. In turning corners the cord passes around pulleys $s^2 s^3$, as shown in Fig. 1. The pulleys are grooved and made of considerable vertical thickness. In passing the pulleys the fork of the carrier which holds the cord runs outside the pulley, bearing upon its edge, and is carried around in that condition without slipping down vertically. As soon as the fork has passed the pulley, the cord falls back into the groove. The enlargements on the cord are not of sufficient size to prevent the cord running in the groove of the pulleys.

Having described my invention, what I claim as new and desire to secure by Letters Patent, is—

1. In a parcel-carrier, the combination, with the main track A, of the pivoted elevator-arm I, the pivoted switch K, and a jointed connection between said arm and switch, whereby when the arm is raised to run the carrier onto the main track the switch will be raised from the main track, as and for the purpose specified. 50

2. In a parcel-carrier, the combination of the pivoted arm I, the pivoted switch K, a jointed connection $c^2 d^2$ between said arm and switch, the link u, attached to the arm and provided with a socket v sliding on a way, and a cord e, for raising the arm, as herein shown and described. 55

3. In a parcel-carrier, the combination of the pivoted arm I, the link u, attached thereto and provided with a socket v sliding on a way, a cord e, for operating the arm, and a spring-hook h², for holding the free end of the arm, as shown and described, and for the purpose specified. 60

4. In a parcel-carrier, the combination, with the switch-track C, of the pivoted spring-arm L, arranged to connect with the carrier as it passes around the circle, and a disconnecting device to free the arm from the carrier at the end of its sweep, as herein shown and described. 65

5. The combination, with the carrier-head provided with notches l l, of the slide H, resting therein and movable vertically, the laterally-projecting stud m', attached to the slide, the shank k', pivoted to the slide and provided with a dog k that engages with the notches, and a spring k⁴, which presses the dog into engagement with the notches and allows its retraction to change the adjustment, as herein shown and described. 80

In witness whereof I have hereunto signed my name in the presence of two subscribing witnesses.

HENRY B. WILLIAMS.
